UNITED STATES PATENT OFFICE.

ISRAEL L. LANDIS, OF LANCASTER, PENNSYLVANIA.

SWINGING GATE.

SPECIFICATION forming part of Letters Patent No. 256,331, dated April 11, 1882.

Application filed December 15, 1881. (Model.)

To all whom it may concern:

Be it known that I, ISRAEL L. LANDIS, of Lancaster, in the county of Lancaster, and in the State of Pennsylvania, have invented certain new and useful Improvements in Gates; and I do hereby declare that the following is a full, clear, and exact description thereof, reference being had to the accompanying drawings, and to the letters of reference marked thereon, making a part of this specification.

My invention relates to swinging gates and the appurtenances therefor, as will be herein-after fully explained.

Figure 1 is a side elevation of my new gate, showing it in dotted lines adjusted above and below a horizontal plane. Fig. 2 is a vertical cross-section taken transversely through the gate in the plane indicated by dotted line $\alpha\alpha$ on Fig. 1. Fig. 3 is a detail showing the vertical adjustability of my gate. Fig. 4 are perspective views, showing both parts of my hinge. Fig. 5 is a top view of the gate.

Similar letters of reference indicate corresponding parts.

A designates the gate-post, which is fixed into the ground in any suitable manner. To this post are secured the pintles B B, upon which my improved gate is hinged.

B' B' designate the clip-eyes, which connect the gate C to the post A, so that it will swing horizontally. These clip-eyes will be herein-after fully explained.

The gate C is composed of two rear battens, D D, to which the clip-eyes are attached, two battens, E E, and parallel rails F. The rails F are pivoted between the battens D D and E E, so that however high or low the free end of the gate may be raised or lowered the rails will preserve their parallelism.

F' designates a batten, which is pivoted to each rail of the gate, so that it will preserve its parallelism with respect to the rear battens, D, and the battens E.

To the top and bottom rails, at $\alpha\alpha$, I suitably pivot two diagonal braces, G G, which cross each other at an angle between a fixed stud, b, and a through-bolt, c. These braces have free end-play between said stud and bolt. The bolt c passes through the batten F and through one of the gate-rails, and also through

the lower end of a flexible clamp or grip, H; and it is a pivot.

Above the fixed stud b and the angle of crossing of the two braces G G is a bolt, g, which is rigid to the batten F, and which forms a pivot for the rail, through which it passes, and also a pivot for the clamp or grip H. The end of this bolt nearest the grip H receives a washer and a hand-crank, J.

It is obvious from the above description that the pivotal portions which connect the gate-rails to their end battens can be set free by turning the crank J in one direction, and that by turning this crank in an opposite direction the free end of the gate can be raised or lowered above and below a horizontal plane, and then fixed. In whatever position the gate may stand when fixed by the clamp-crank and grip it will swing freely about its hinges. The grip H should be made of a suitable springy wood.

In order to properly hang my gate, I employ the pintles B B and the clip-eyes B' B', as above referred to. The clip-eyes are respectively composed of an eye, h, a neck, h', and bifurcations i i, the free ends of which are turned inwardly, so as to form hooks, as shown at j j. Such clip-eyes are especially adapted for gripping and clamping the two rear battens, D D, and when used in combination with the wedges W W, driven as shown in Fig. 1, they are rigidly fixed to said battens. They bind the battens or pivotal portions or portion laterally as well as longitudinally, and they prevent any possibility of the gate settling. These clip-eyes as constructed by me also prevent the rear uprights or pivotal portions of the gate from settling.

I have referred to a gate having two battens, D D; but I may use a single piece of wood properly mortised to receive the rails, to which my clips may be applied. Therefore I do not confine myself to the use of two independent battens.

By removing the wedges W W the gate can be adjusted and then fixed to swing as above described.

I claim as my invention—

1. The combination of the end battens and the intermediate batten pivoted to the gate-rails, the diagonal endwise movable braces,

also pivoted to the gate-rails and crossed, the stud *b* and bolt *c*, between which said crossed portions of the braces play, the flexible clamp or grip *H*, and means, substantially as described, for binding the parts rigidly together.

2. In a vertically-adjustable gate having diagonal crossed braces guided by the stud *b* and bolt *c*, the combination of the pivotal through-bolt, the clamp or grip *H*, the bolt *g*, and a hand crank, *J*, substantially as described.

In testimony whereof I affix my signature, in presence of two witnesses, this 15th day of December, 1881.

ISRAEL L. LANDIS.
